GAS SCRUBBER

Standen Leonard Pearce, London, England, assignor of one-half to London Power Company Limited, London, England

Application March 16, 1933, Serial No. 661,169,
and in Great Britain March 19, 1932

2 Claims. (Cl. 261—108)

This invention relates to scrubbers for gas-washing or purification or for other treatment of gases with liquids in either co-flow or counter-flow directions, and has for its object to devise an improved form of scrubber by means of which very intimate contact between the gas and the treating medium may be attained without undue interference with the flow of the gases by resistance to their passage through the scrubber.

The invention consists in a scrubber comprising a series of boards or plates arranged in a number of superposed rows or layers, the boards or plates of one row or layer sloping downwards in one direction while those in the next adjacent row or layer slope downwards in the opposite direction and so on throughout the series.

The invention also consists in a scrubber of the above character having at the upper edge of each board or plate a fillet or strip so disposed as to catch the liquid from a higher layer and conduct the same to the under-side of the board or plate of the next lower layer.

Further features of the invention will be apparent from the description given hereafter.

The accompanying drawing illustrates several modes of carrying out the invention.

Figure 1 is a sectional elevation of one form of scrubber in accordance with the invention.

Figure 2 illustrates more or less diagrammatically a modification.

Figure 3 is a section showing a modified detail, and

Figure 4 is a broken front elevation of a board or plate.

In carrying my invention into effect in one convenient manner when, for example, devising a scrubber suitable for use with a process for cleaning or purifying flue gases or the like, I form my scrubber with an outer casing *a* and a number of superposed rows or layers each comprising a plurality of boards *b* or plates of wood, metal or other suitable material, and of any convenient dimensions, the layers of plates or boards running horizontally across the tank, or chamber within the casing or tower *a* in which they are arranged.

The boards or plates of the respective layers are parallel to one another and arranged at an inclination to the horizontal, those in one row, for example, sloping downwards towards the left while those in the next adjacent row slope downwards towards the right and so on throughout the whole series of rows or layers.

Each board or plate is provided at its upper edge with a strip or fillet *c* which may be secured upon the face of the plate as shown in Figure 1 or upon the edge thereof as shown in Figure 3 and which is disposed substantially at right angles to the plate or board and the outer

upper edge of the latter or of the fillet is rounded and the lower edges of the boards of one layer are so disposed relative to the fillets of the next lower layer that the liquid from a higher layer is caught by the fillet and is conducted to the under-side of the board or plate of the lower layer.

The boards or plates of each layer are spaced apart (conveniently so that the upper edge of one board or plate slightly overlaps the lower edge of the adjacent board or plate) and the layers or rows may also themselves be somewhat spaced apart and the arrangement is such that while very intimate contact between the gas and the treating liquid can be obtained there will be no undue resistance to the passage of the gas through the scrubber.

When the plates or boards show a tendency to sag or warp in such a manner as to collect the flow of washing medium to a greater extent at one part of the board than at others I may ensure a substantially even flow of washing medium over the whole length of each board or plate by providing the lower edge with a serrated or like formation *d* as shown in Figure 4.

Figure 2 shows a series of scrubber plates *f* formed of metal in which the fillet *c* at the upper edge of each board is formed as a flange by bending the metal plate.

The invention is applicable to scrubbers for gas-washing or similar operations where the flow of the gas and treating medium is in the same direction or in opposite directions and I may vary the number and shape of the individual plates or boards and the manner of disposing the layers relatively to one another depending upon the particular purpose for which the scrubber is to be employed or any practical requirements that may have to be fulfilled.

I claim:—

1. A gas scrubber comprising a series of boards or plates arranged in a number of superposed rows, the boards or plates of one row sloping downwards in one direction while those in the next adjacent row slope downwards in the opposite direction and at the upper edge of each board or plate a fillet or strip so disposed as to catch the liquid from a higher row and conduct the same to the under-side of the board or plate of the next lower row.

2. A gas scrubber comprising a series of metal plates arranged in a number of superposed rows, the plates of one row sloping downwards in one direction while those in the next adjacent row slope downwards in the opposite direction and each plate being bent over at its upper edge to form a flange or fillet disposed to catch falling liquid and direct the same to the under-side of the plate.

STANDEN LEONARD PEARCE. 120
